UNITED STATES PATENT OFFICE.

MILTON H. SHOENBERG, OF SAN FRANCISCO, CALIFORNIA.

SOCKET-INTERRUPTER.

1,400,914.

Specification of Letters Patent. Patented Dec. 20, 1921.

Application filed May 13, 1920. Serial No. 381,148.

To all whom it may concern:

Be it known that I, MILTON H. SHOENBERG, a citizen of the United States, and a resident of the city and county of San Francisco, 5 State of California, have invented new and useful Improvements in Socket-Interrupters, of which the following is a specification.

My invention has for its object the provision of a device adapted to be introduced 10 into the well known electric lamp socket, and between the central contact therein and the corresponding contact surface of the base of an incandescent lamp or other socket device, whereby current is alternately permitted to flow and to be interrupted at periodic intervals through the action of the said device.

This object I attain by mounting within 20 my device an element sensitive to heat and adapted when heated to move over a sufficient distance to interrupt a circuit previously completed therethrough.

This heat sensitive element is mounted adjacent to an electric resistance through which 25 the energizing current of the socket connected device, whether lamp, electric iron, etc., will be permitted to flow at such times as the heat sensitive element is below a predetermined temperature, and if the said element is heated as by the resistance coil beyond the predetermined point; the said heat element thereupon is distorted by the said heat into a shape whereby the current previously flowing is interrupted. It therefore 30 follows that the said heat element will thereafter continue to cool until it cools below the predetermined point and contact is again effected, and current permitted to flow. There will, therefore, be a periodic make- 35 and-break in the energizing circuit of such a socket device wherein my invention is introduced.

By referring to the accompanying drawings, my invention will be made clear.

40 Figure 1 is a perspective view of an ordinary lamp and socket partly broken away to show my device in place.

Fig. 2 is a section through my interrupter on the line II-II of Fig. 3.

45 Fig. 3 is a section in plan on the line III-III of Fig. 2 and at right angles thereto.

Fig. 4 is a detail view of the contact parts and thermostat terminals.

Throughout the figures like numerals refer to identical parts. 55

A lamp socket of well known form is indicated by the numeral 1, within which is mounted the lamp 2.

Referring particularly to Fig. 1, my device in preferred form is shown full size at 60 3 and is as follows. A shallow cup-shaped metallic member 4 has centrally fixed therein a pin 5, preferably headed and extended to contact with an insulated lining of a similar cup-shaped member on the opposite side and indicated at 6.

The layer of insulation protecting the inner surface of 6 is shown by the numeral 7, and is formed concentric with and for the 70 purpose of lining the cup member 6; a similar lining is provided for the cup member 4, as indicated at 8, so that when the members 4 and 6, and their linings are slipped together with their peripheries in engagement 75 an annular closed compartment is formed with the two members insulated from each other and providing an interior insulating surface.

The pin 5 prevents the collapsing of the 80 members 6 and 4, and there is then provided an insulating rim of annular shape pressed over the member 6 and as shown at 9 and 10, and which I have shown as made of two annular rings. Within the annular compartment formed between the plate members 4 and 6, and attached to the central pin 5, I provide an arm preferably made of iron and indicated by the numeral 11, which arm extends first radially and then turns forming 85 a concentric circular member in the said compartment, and attached to the periphery of this circle is a concentric metallic bar preferably of different metal, as zinc, and indicated by the numeral 12. Other metals may 90 be substituted for iron and zinc, the essential feature of the combination being that they be of different co-efficients of expansion to 95 secure the best results.

An electric terminal 13 is fitted at one end 100 of the combined thermal element 11, 12, and on the opposite side is provided a layer of insulation 14, and a second electric terminal 15. To one of these terminals, 15, is to be attached an electrical resistance indicated at 105 16 as of helical spring form, and which may be wound upon a fiber rod or strip 17 (see Fig. 4). The opposite terminal of this wire

as at 18 is carried through the metallic cap 6 and riveted, or soldered, and this establishes electric conductivity from metallic cap 4 and pin 5 through the ring 11, 12, and the terminal 13 and when thermal coil 11, 12 is below the critical temperature, contact is made from 13 to 15 (see Fig. 4), the path is then through the resistance 16 connecting wire 18 and the metal cup 6.

- 10 It will thus be seen that a circuit may be completed between the surface of the plate 4 and the surface of the plate 6 whenever the temperature is below the critical temperature; and the flow of electric current over 15 the said circuit heats the coil 16, which in turn heats the thermal coil 11, 12, causing its relative expansion and the separation of the contact 13 from the contact 15, thus interrupting the circuit. The current now being cut off from the resistance 16, the device and its associate parts begin to cool and the contact is thereafter reestablished between 20 13 and 15 and the cycle of movements is repeated indefinitely. It will thus be seen that 25 with the device of my invention the lamp will be periodically lighted and extinguished, as for purposes of display or otherwise and may be used for maintaining constant temperature in an electric iron, or similar devices.

30 It will be noted that the column 5 pre-

vents the collapsing of the plates 6 and 4 when the lamp socket is secured against my device.

Having thus described my invention, what I claim and desire to secure by Letters Patent is:

1. A circuit interrupting device comprising an upper and a lower shell adapted to telescopically engage at their peripheries, insulating material between the shells, a thermostat element carrying contacts constructed and adapted to break contact with each other when heated and to make contact when cooled and the said element and one shell and one contact connected in electric series and the other contact and the other shell also connected in electric series. 40 45

2. A circuit interrupting device as set forth in claim 1 wherein a pin is fixed to one of the shells forming a strut against the insulating lining of the other shell to resist compression of the shells and wherein the thermostat element is supported from said pin. 50 55

3. A device as set forth in claim 1 having an outer ring of insulating material and constructed and adapted to fit into an electric socket.

In testimony whereof I have hereunto set my hand at San Francisco, California.

MILTON H. SHOENBERG.
